(57) **CLAIM**

I claim the ornamental design for folding door with mini slats, as shown and described.

DESCRIPTION

FIG. 1 is a front elevational view of the folding door with mini slats without surface ornamentation. The oval circle at the

upper left in FIG. 1 referencing a detail of the front of the folding door in FIG. 2 and the oval circle on the right in FIG. 1 referencing another detail of the front of the folding door in FIG. 3. The rear view of the folding door shown in FIG. 1 being a mirror image of the front view.

FIG. 2 is an enlarged front view of the folding door with mini slats taken from the upper left in FIG. 1.

FIG. 3 is an enlarged front view of the slats of the folding door with mini slats taken from the upper central area of FIG. 1.

FIG. 4 is a bottom view of the folding door shown in FIG. 1.

FIG. 5 is a top view of the folding door shown in FIG. 1.

FIG. 6 is a left side view of the folding door shown in FIG. 1.

FIG. 7 is a right side view of the folding door shown in FIG. 1.

FIG. 8 is a front elevational view of the folding door with mini slats with a wood grain surface ornamentation. The oval circle at the upper left in FIG. 8 referencing a detail of the front of the folding door in FIG. 9 and the oval circle on the right in FIG. 8 referencing another detail of the front of the folding door in FIG. 10. The rear view of the folding door shown in FIG. 8 being a mirror image of the front view.

FIG. 9 is an enlarged front view of the folding door with mini slats taken from the upper left in FIG. 8.

FIG. 10 is an enlarged front view of the slats of the folding door with mini slats taken from the upper central area of FIG. 8.

FIG. 11 is a bottom view of the folding door shown in FIG. 8.

FIG. 12 is a top view of the folding door shown in FIG. 8.

FIG. 13 is a left side view of the folding door shown in FIG. 8; and,

FIG. 14 is a right side view of the folding door shown in FIG. 8.

The broken away sections illustrate indefinite length and width of the claimed design.
